FIG. 1 is a top perspective view of an inventory management device;
 FIG. 2 is a front elevation view thereof;
 FIG. 3 is a rear elevation view thereof;
 FIG. 4 is a right side elevation view thereof;
 FIG. 5 is a left side elevation view thereof;
 FIG. 6 is a top plan view thereof;
 FIG. 7 is a bottom plan view thereof;
 FIG. 8 is a top perspective view thereof;
 FIG. 9 is a top perspective view thereof in a container shown in an upright position;
 FIG. 10 is a top perspective view thereof shown in a down configuration;
 FIG. 11 is a top perspective view thereof shown in an upright configuration; and,
 FIG. 12 is a top perspective view thereof shown in a down configuration.
 The broken line disclosure of the container is for illustrative purposes only and forms no part of the claimed invention.
